POP-GUN.

No. 815,223.

Specification of Letters Patent.

Patented March 13, 1906.

Application filed April 29, 1905. Serial No. 258,015.

To all whom it may concern:

Be it known that we, JOSEPH SEIBOLD, THOMAS CURRAN, and MILTON L. BACON, citizens of the United States, residing at Antigo, in the county of Langlade and State of Wisconsin, have invented new and useful Improvements in Pop-Guns, of which the following is a specification.

This invention has relation to toys of the class known as "film-bursters" or "pop-guns;" and it is the object of the invention to provide such improvements as will render the toy entirely harmless, enhance the enjoyment that may be obtained in its use, and make it handier and more efficient in the ways and for the purposes for which it is intended to be employed than heretofore.

The invention consists of the improvements hereinafter fully described, and illustrated in the accompanying drawings, which latter form a part of this specification and are to be referred to as such.

Of the drawings, Figure 1 is a side view of the invention, showing the piston-rod as drawn back preparatory to firing. Fig. 2 is a similar view showing the gun as having just been fired. Fig. 3 is a longitudinal sectional view showing the piston-rod as being partially withdrawn. Fig. 4 is a plan view of a gun cap or wad. Fig. 5 is a perspective view of the barrel-cap to hold a gun-cap on the end of the barrel. Fig. 6 is a representation of the end of the barrel for the reception of the gun and barrel caps.

Of the drawings, *a* designates the barrel of the gun, which may consist of a length of metal tubing or be composed of other suitable material, which is closed at one end excepting a central opening *b* in the closure for the reception of the piston-rod *c* and another small opening *d* for the admission and expulsion of air behind the piston *e* as the latter is reciprocated in the barrel. The piston-rod *c* is provided on its outer end with a suitable knob or handle *f*, by which it may be operated, and the piston *e* is properly packed, as shown at *g*, to render it as nearly air-tight in its operation as is necessary.

The muzzle of the gun is provided with a ferrule *h*, which is shrunk or otherwise secured thereon, from the opposite sides of which project pins *i*. A barrel-cap *j* is provided of such size as to fit fairly snugly over the ferrule *h* and has an annular inwardly-

projecting flange *k*, which abuts against the ferrule and end of the muzzle to hold the margins of the caps with the requisite security. This is an important feature of the improvement. At opposite sides the barrel-cap is provided with slots *l* for the reception of the pins *i* in such manner that the pins may first enter the slots and allow the barrel-cap to be turned after the manner of a bayonet-joint, securing the barrel-cap in place on the ferrule. This means of connecting the barrel-cap with the muzzle is important as being handy in the extreme and quickly effected by the user, which is important.

m is a gun cap or wad consisting of a disk of paper or other suitable substance of a form to fit within the barrel-cap *j* and rest on the flange *k*. When the gun-cap is thus placed and the barrel-cap secured in place on the muzzle of the gun, it will be held securely in position substantially air-tight with respect to the interior of the barrel, and the gun is in loaded condition. By drawing the piston-rod back and forcing it forward with a quick motion the gun will be "fired" by the bursting of the gun-cap from the force of the air in the barrel, giving a loud sharp report, to the amusement of children and others and without the slightest danger of harm to any one. Where the gun-cap is made of strong material, the cap will not be broken or exploded, but be simply forced from place held by the barrel-cap, though with the same effect as though broken by the force of the air acted upon by the piston-rod, and under these circumstances the gun-cap may be reused.

It is obvious from the construction that the barrel-cap can be quickly and easily removed and a fresh gun-cap placed in the barrel-cap, when the latter may be replaced, and the gun will be again in loaded condition, ready for another firing operation.

The inclination of the lateral portion of the slots in the barrel-cap which forms the bayonet-joint connection before mentioned makes provision for drawing the annular flange of the barrel-cap on which the margin of the gun-cap rests quite tight against the muzzle of the gun, so that the gun-cap is held against being accidentally displaced by the force of the air from the barrel and "misfire" is not likely to occur.

The ferrule, in addition to other functions, provides a broader surface on the end of the

muzzle for holding the margin of the gun-cap between the latter and the flange of the barrel-cap than would be afforded if the gun-barrel alone were relied upon for this purpose.

It is to be observed that parts of the invention may be employed with so-called "film-bursters" and air-guns, and its employment therewith is not precluded if it should be found useful in said connections. It will be observed, moreover, that the toy, while quite complete as a pop-gun, is very simple in construction and manner of operation and the cost of its use is almost *nil*.

15 We claim—

1. A pop-gun comprising in its construction a barrel and piston-rod provided with a piston, in combination with a barrel-cap having an inwardly - projecting annular flange 20 adapted to be secured on the muzzle of the gun, and a gun-cap constructed to be inserted in the barrel-cap and to exactly fit therein and to rest on the said muzzle and ferrule and to be bound between the same and the 25 inwardly-projecting flange of the barrel-cap.

2. A pop-gun comprising in its construction a barrel provided on its muzzle with a ferrule, and piston-rod provided with a piston, in combination with a barrel-cap provided with an inwardly - projecting flange 30 adapted to carry a gun-cap fitting exactly therein with its margin resting on said flange

and to bind the same on the muzzle and ferrule of the gun, and means, comprising a bayonet-joint, for readily and quickly securing the 35 barrel-cap and gun-cap in place on the muzzle.

3. The combination with a pop-gun barrel having a ferrule secured to its muzzle, of a gun-cap, and barrel-cap provided with an inwardly-projecting flange adapted to rest on 40 the end of the muzzle and bind the margin of the gun-cap therebetween, the gun-cap being of a size to fit in the barrel-cap with its margin resting on the said flange.

4. The combination with a pop-gun barrel 45 having a ferrule secured to its muzzle, of a gun-cap and barrel-cap provided with an inwardly-projecting flange adapted to rest on the end of the muzzle and ferrule, and bind the margin of the gun-cap therebetween, the 50 gun-cap being of a size to fit in the barrel-cap with its margin resting on the said flange, and means comprising a bayonet-joint for securing the barrel-cap in place.

In testimony whereof we affix our signatures in presence of two subscribing witnesses.

JOSEPH SEIBOLD.
